UNITED STATES PATENT OFFICE

SIDNEY E. THOMPSON, OF WEST ENGLEWOOD, NEW JERSEY, ASSIGNOR TO COPELAND & THOMPSON, INCORPORATED, OF NEW YORK, N. Y., A CORPORATION OF NEW YORK

DESIGN FOR A COVERED DISH

Application filed March 12, 1931. Serial No. 39,054. Term of patent 14 years.

To all whom it may concern:

Be it known that I, SIDNEY E. THOMPSON, a subject of the King of Great Britain, residing at West Englewood, in the county of Bergen and State of New Jersey, whose post-office address is 350 Ogden Avenue, West Englewood, New Jersey, have invented a new, original, and ornamental Design for a Covered Dish, of which the following is a specification, reference being had to the accompanying drawings, forming part thereof.

In the drawings:

Figure 1 is a top plan view of a covered dish according to my new design.

Figure 2 is a plan view of such a dish with the cover slightly raised.

The dish of my design is relatively shallow compared with its length, has a wide, sloping rim, and has a standard or pedestal be-

low the dish proper. The cover in contrast to the dish, is tall in proportion to its length and its sides extend at a slight angle to the vertical for about one-third of its height, then slope sharply and uniformly inwardly to the narrow flat top on which the rounded, scalloped handle is set.

A feature contributing greatly to the beauty of this design is the sharpness of the curves and angles therein resulting from the sudden changes in the contour of the rim, dish proper and standard, and in the sharp upward slope of the sides of the cover beginning at a point a short distance above its lower edge.

I claim:

The ornamental design for a covered dish, as shown and described.

SIDNEY E. THOMPSON.
